UNITED STATES PATENT OFFICE

2,277,079

STAPLE FIBER CUTTER

Hobart O. Davidson, Swarthmore, Pa., assignor
to American Viscose Corporation, Wilmington,
Del., a corporation of Delaware

Application September 25, 1941, Serial No. 412,237

7 Claims. (Cl. 164—61)

The invention relates to the cutting of staple fibers from bundles of continuous filaments and more particularly to that type of apparatus which involves the use of centrifugal force in drawing the bundle of filaments to be cut into the path of a knife, such as is described in the Beria Patent 1,723,998.

In using this type of apparatus, a certain amount of twist always is associated with the filament bundle because of the rotation of the radially extending portion of the bundle about the axis of the filament bundle as it is fed into the rotating disc. The amount of twist depends upon the rapidity of feed of the bundle to the disc and speed of rotation of the disc. Since this twisting occurs about the axis of the filament bundle, the lengths of the filaments surrounding the central filaments of the bundle are of increasing length as they occupy a greater distance from the center of the bundle, such comparative lengths being taken over a given unitary length of the bundle. Since the twist is present in the filament bundle at the position of cutting, the result is a non-uniformity in the lengths of fibers cut therefrom. It is an object of this invention to so modify the apparatus of this type as to provide an independent control over the amount of twist present in the filament bundle as it emerges from the rotating disc into the cutting knife. This controlling means provides a way of obtaining either decreased or increased twist in the filament bundle as it emerges from the disc or it may be operated in such a manner as to substantially entirely remove the twist imparted to the bundle by virtue of the rotation of the disc about its axis and about the axis of the bundle as it is fed to the disc.

In the drawing, illustrative of the invention, Figure 1 is a plan view of the modified device, Figure 2 is a front elevation of the device, partially in cross-section, and

Figure 3 is a front elevation of a modified form of the invention.

In Figures 1 and 2 of the drawing, the disc 2 mounted on the shaft 3 for rotation is provided with the customary funnel-like opening 4 for receiving the bundle of filaments fed thereto, and is provided with a sleeve 5 rotatable therein and having its inner bore 6 in register with the axially extending bore 7 in the disc 2. There is provided a support 8 for the knife 9 which has its cutting edge disposed adjacent or substantially in contact with the periphery 10 of the disc 2. The disc 2 is further provided with the opening 11 to accommodate the gear 12 which is secured to the

5 rotatable sleeve 5 for rotation therewith. Supported in the bearings 13 and 14 of the support 8, there is a hollow shaft 15 concentric with shaft 3 and provided with a pulley 16 by which it may be driven independently of shaft 3. The upper end of the hollow shaft 15 is provided with a gear 17 which meshes with the gear 12 for rotating the hollow sleeve 5 in the disc 2.

10 The extent of untwisting or additional twisting which may be imparted to the filament bundle by rotatable sleeve 5 depends upon the length of the sleeve, the frictional characteristics of the interior surface of the sleeve with respect to the filament bundle, and the speed of rotation and direction of rotation of the sleeve.

15 The twisting of the filament bundle about its axis as it enters the rotating disc results in an S-twist by virtue of the counterclockwise rotation of the disc as viewed in Figure 1. In operation of the device in accordance with the invention, gear 17 may be held stationary, thus increasing the S-twist by virtue of rotation of gear 12 on the sleeve about the stationary gear. By rotating the gear 17 clockwise as viewed from the top of Figure 1, the S-twist may be still further increased. On the other hand, by rotating the gear counterclockwise as viewed from above Figure 1, the S-twist may be decreased partially or entirely or by further increasing the speed of rotation of this gear in this direction, the filament bundle may be given a Z-twist.

20 In Figure 3, a modification is shown in which the support 19 carries the knife 9 and a stationary bevel gear 18 arranged to mesh with the gear 12 carried by the disc 2 in the same manner as is shown in Figures 1 and 2. In this arrangement no rotation of gear 18 is necessary to effect untwisting of the tow as it passes through the disc 2. If desired, gear 18 may be mounted for rotation, in which event any desired extent of twisting or untwisting may be obtained.

25 Thus, the device of this invention affords a means which may be controlled to obtain any desired diversity in the lengths of the fibers cut from the filament bundle as well as means whereby the twist may be entirely removed from the bundle to produce fibers having substantially uniform lengths.

30 While a preferred embodiment of the invention has been disclosed, the description is intended to be illustrative only, and it is to be understood that changes and variations may be made without departing from the spirit or scope of the invention as defined by the appended claims.

What I claim is:

1. An apparatus of the character described comprising cutting means, centrifugal means for directing a bundle of filaments periodically to said cutting means, and means associated with said cutting means for controlling the twist imparted to said filament bundle by said cutting means before the bundle enters said cutting means.

2. An apparatus of the character described comprising cutting means, centrifugal means for directing a bundle of filaments periodically to said cutting means, and means for controlling the twist in said filament bundle as it approaches said cutting means.

3. An apparatus of the character described comprising cutting means, centrifugal means for directing a bundle of filaments periodically to said cutting means, and means comprising a member rotatable about an axis extending radially within said centrifugal means for controlling the twist in said filament bundle as it approaches said cutting means.

4. An apparatus of the character described comprising cutting means, centrifugal means comprising a radial channel for directing a bundle of filaments periodically to said cutting means, a sleeve rotatable within said centrifugal means about its axis and having its bore disposed to constitute at least a portion of said radial channel, and means for rotating said sleeve with respect to said centrifugal means.

5. An apparatus of the character described comprising a rotatable disc, a channel therethrough having a generally axially extending portion and a radially extending portion, a cylindrical sleeve surrounding at least part of said radially extending portion, means for rotating said disc and means for rotating said sleeve about its axis.

6. An apparatus of the character described comprising a rotatable disc, a channel therethrough having a generally axially extending portion and a radially extending portion, a cylindrical sleeve surrounding at least part of said radially extending portion, cutting means adjacent the periphery of said disc, means for rotating said disc and means for rotating said sleeve about its axis.

7. An apparatus of the character described comprising a rotatable disc, a channel therethrough having a generally axially extending portion and a radially extending portion, means for feeding a filamentary bundle into the first-mentioned portion of said channel, a cylindrical sleeve surrounding at least part of said radially extended portion, cutting means adjacent the periphery of said disc, means for rotating said disc and means for rotating said sleeve about its axis at a speed sufficient to remove from said bundle the twist acquired by virtue of the rotation of said disc.

HOBART O. DAVIDSON.
